United States Patent Office.

ASA HILL, OF NORWALK, CONNECTICUT.

Letters Patent No. 93,086, dated July 27, 1869.

IMPROVED COMPOSITION DENTAL PLATE.

The Schedule referred to in these Letters Patent and making part of the same.

To all whom it may concern:

Be it known that I, ASA HILL, of Norwalk, in the county of Fairfield, and State of Connecticut, have invented certain new and useful Improvements in Compound or Preparation for Artificial Gums, or Plates, or Base for Teeth; and do hereby declare that the following is a full, clear, and exact description thereof.

To enable others skilled in the art to construct and use my invention, I will proceed to describe it.

The object of this invention is to furnish artificial gums, or dental plates, or bases for teeth, which afford the requisite qualities of strength, toughness, and durability, as well as ease and facility of adaptation, and to obviate the difficulties and obstacles incident to the application of all the different methods of doing the same at present known to the dental profession, as also to greatly facilitate the mounting or setting of artificial teeth, and attaching them to the base or dental plates.

This process requires no heat, swaging, or vulcanization, and reduces the process to the last simplicity.

The materials employed for this purpose are—

First, collodion of gun-cotton, dissolved in ether and alcohol, combined with various substances to give it color and body, and prevent its explosive effects or qualities.

Second, fibrous, textile, or pulpy materials, such as paper, either in pulp or in form, cotton, linen, woollen, or silk, whichever may be preferred.

Third, perforated metal plates, of gold, silver, aluminum, platinum, iron, or zinc, or wire gauze, or cloth of any suitable kind.

The following is a clear and faithful description of my method of preparing the same for use, and their application to the objects and purposes herein set forth.

I first dissolve a sufficient quantity of prepared cotton or collodion in ether and alcohol, in which is combined fine asbestos, with mineral oxides, to give it color, such, for instance, as red oxide of iron, sometimes adding oxide of zinc, and other substances of like character, for the purposes previously named.

Having my solution ready, I next take a fine plaster model of the mouth, and proceed to adapt the material for forming my artificial dentine as follows:

Method No. 1.

I first cut a pattern for my plate, of paper, adapted to the model. From this paper pattern I cut several of the same form, muslin, woollen, silk, or woollen, according as the plate is to be thick or thin.

I then saturate the same in my solution, and press them, with my fingers, over the model, until they adapt themselves to all the inequalities of surface and form, and until they become a perfect fit. These sev-

eral layers thus become connected together in one mass, quite homogeneous, thus constituting my dental plate or base.

I then select my teeth for mounting, and having adjusted them in position, proceed to cement them to the plate or base by the same solution. This may be laid on with a small spatula, or other instrument adapted to the purpose, and as layer after layer is thus laid on and around the teeth, giving sufficient time for evaporation, the material shrinks around the teeth, binding them firmly to the base, and when finished, present the natural appearance of the gums and the form of the alveoli or jaw.

This is all accomplished without heat, or dies, or pressure of any kind, save what is sufficient to mass the materials together, and hold them in position until they become hard and stiff by evaporation of the ether and alcohol.

Method No. 2.

I proceed, as before, to cut two or more lamina, of muslin, silk, or linen, woollen, or paper, as the case may be. One of these lamina I saturate with the solution, and mould it over the model.

I then take any perforated metal, wire gauze, or cloth, having previously shaped it to the form of the plaster model, by pressing it over the same, and burnishing it down upon the model until it becomes a perfect fit, and laying it over the first lamina, cement it together by filling the interstices with the solution, and holding it in place until it becomes fixed by cementation.

After this I saturate another lamina, and spread it over the whole, taking care to press and consolidate the whole together, thus forming my dental plate or base, after which the teeth are mounted, as before.

Method No. 3.

I take felt or woven cloth, either with or without color, preferring the pure white felt, of suitable thickness, and after cutting it the right size and form, saturate it thoroughly with the solution until it becomes interwoven with the fibres of the cloth, and then proceed to mould upon the model, as before.

This base is so nearly homogeneous, so flexible in moulding, and, withal, so solid and compact when finished, that I prefer it to any of the processes yet mentioned.

When felt or woven cloth is thus treated, and fully settled upon the model, it supplies the lightest and strongest dental plate or base with which I am acquainted; and it is very easily adapted to any required case, and secures the most perfect adaptation to any inequalities of form of any material now in use.

If need be, the plates or base thus prepared may be

strengthened or built up in any part at discretion, by spreading over and upon it the solution before named.

Plates formed of these materials, and in the manner herein described, fulfil more perfectly all the indications and necessities of the dental profession, in a manner far more simple, complete, and effective, than any known materials now in use; and in case of accident, by breaking a tooth, it can be replaced with the greatest facility, and be just as good as if it had never been injured or removed, and the whole piece present a uniform appearance, as before the accident.

The method of repairing is simply to adjust the parts, and cement the whole together, as if nothing had occurred, by means of the solvent; and I believe this is the only material ever successfully used for sticking the teeth to the plate or base, with perfect success, and that, too, without heat of any kind.

I am aware that different kinds of gums, resins, shell, &c., have been employed for this purpose, but always with only temporary success. The very nature of the materials employed preclude the idea of permanence, when subjected to the heat and fluids of the mouth.

In case the plates should spring or warp, they may

be readjusted, by immersing them in ether and alcohol for a few moments, and then shaping them again upon the model, as desired.

I do not confine myself to the same exact proportions in making my compound solutions, but may vary them, as taste, convenience, or peculiarity of the circumstances may require; nor do I confine myself to the same number of lamina, or to precisely the same material, in all cases, but may vary them as to the number or kind, whether cotton, linen, silk, woollen, or any other fibrous or textile material.

Having thus described my invention,

What I claim, is—

1. A dental plate, formed of cotton, woollen, silk, linen, paper, or any similar textile or fibrous material, combined with collodion, substantially as described.
2. The use of perforated metal plates or wire gauze, substantially in the manner herein described.
3. The method of securing teeth to the plate, by means of collodion, as herein described.

ASA HILL.
